(57) **CLAIM**

The ornamental design for a vehicle with sensor housings, as shown and described.

DESCRIPTION

FIG. 1 is a top, front, right-side perspective view of a vehicle with sensor housings;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof;

FIG. 8 is an enlarged top perspective view of the right-side sensor housing, shown separately for ease of illustration;

FIG. 9 is a bottom perspective view thereof;

FIG. 10 is another bottom perspective view thereof;

FIG. 11 is a front view thereof;

FIG. 12 is a back view thereof;

FIG. 13 is a right-side view thereof;

FIG. 14 is a left-side view thereof;

FIG. 15 is a top view thereof;

FIG. 16 is a bottom view thereof;

FIG. 17 is an enlarged top perspective view of the left-side sensor housing, shown separately for ease of illustration;

FIG. 18 is a bottom perspective view thereof;

FIG. 19 is another bottom perspective view thereof;

FIG. 20 is a front view thereof;

FIG. 21 is a back view thereof;

FIG. 22 is a right-side view thereof;

FIG. 23 is a left-side view thereof;

FIG. 24 is a top view thereof; and,

FIG. 25 is a bottom view thereof.

(Continued)

The dashed broken lines depict portions of the vehicle with sensor housings that form no part of the claimed design.
